UNITED STATES PATENT OFFICE.

EDWARD HAAS AND MILFORD B. FERGUSON, OF BROOKLYN, NEW YORK.

WRAPPING MACHINE.

Application filed May 12, 1922. Serial No. 560,365.

To all whom it may concern:

Be it known that we, EDWARD HAAS and MILFORD B. FERGUSON, citizens of the United States, residing at Brooklyn, in the county of Kings, in the State of New York, have invented certain new and useful Improvements in Wrapping Machines, of which the following is a specification.

The invention relates to wrapping machines and more particularly to wrapping machines of the type in which the articles to be enclosed in one or more wrappers are advanced through the machine by successive stages, and in which the various wrapper folding operations are performed as the articles pass from one stage to the next or while they are momentarily at rest.

The object of the invention is to improve upon the construction and mode of operation of wrapping machines of the above type in order that the wrapping operations may be more expeditiously and efficiently performed. To this end the invention contemplates a rearrangement of the transport system by which the articles are advanced through the machine. Cooperating with the transport system are improved means for performing the various wrapper folding operations.

The improved transport system comprises a series of intermittently movable carriers on which are mounted a series of equally spaced pockets for holding the articles to be wrapped. During the operation of enclosing the article in the wrapper, the article and its wrapper are first inserted in a pocket of one carrier, which movement partially encloses the article in the wrapper. The partially wrapped article is then transferred to a pocket of a second carrier. The end extensions of the wrapper are left projecting beyond the ends of the pocket. The article while it is in the second pocket is passed between end folders by which the end extensions of the wrapper are folded down against the side folds of the wrapped article. In order that the end folds may be laid directly against the article, one wall of the pocket is made substantially shorter than the article. Fold breakers are provided to perform the usual function of the removed ends of the pocket wall. Upon the completion of the wrapper folding operations the wrapped article is returned to the

first carrier, and preferably to the same pocket on the first carrier in which it was originally inserted.

While the wrapped article is being transferred from the second carrier to the first carrier it pushes into the pocket of the latter a label which has been positioned between the two pockets. The labels are fed into the machine one at a time by any preferred label feeding means. The labels are then transferred from the point at which they are delivered to the machine to the point where they are engaged by the wrapped article and carried into the pocket by which the label is partially folded about the article. The label transfer comprises means for gripping and positively holding the label, means for properly positioning the label between the two alined pockets, and means for releasing the label. In the preferred form of the invention the pocket which holds the wrapped article comes to rest so that the article is on a vertical plane with its longitudinal axis horizontally disposed. The opposite alined pocket is positioned below the article, so that the wrapped article is pushed downwardly, carrying the label with it into the lower pocket. Thus the means for transferring the label from the point of delivery to the machine to the point between the two alined pockets presents the label on a horizontal plane.

The folding of the label about the wrapped article is completed by transferring the wrapped and partially labeled article to a pocket of a third carrier, where the wrapped and labeled article remains a sufficient length of time for the glue to set. It is then discharged from the carrier onto a receiving platform by which it is inserted into a stacking chute which retains the articles until they are removed by the operator. The means for receiving and stacking the wrapped and labeled articles comprise a chute having a yieldingly mounted bottom by which the stacked articles are supported and a swinging platform for inserting each newly wrapped and labeled article into the bottom of the chute.

The preferred form of the invention is illustrated in the accompanying drawings, in which Fig. 1 is a longitudinal vertical section taken on the line 1-1 of Fig. 2; Fig. 2 is a horizontal section taken on the

line 2—2 of Fig. 1; Fig. 3 is an elevation of the left hand end of the machine; Fig. 4 is a section taken on the line 4—4 of Fig. 3; Fig. 5 is a front elevation of the machine, with certain parts removed; Fig. 6 is a diagrammatic view of the transport system and associated parts; Fig. 7 is a rear elevation of the machine, with certain parts left out; Fig. 8 is an enlarged plan, partly in section, of the end folding devices; Fig. 9 is an enlarged section taken along the line 9—9 of Fig. 1, looking in the direction of the arrows; Fig. 10 is a plan of the label transferring device; Fig. 11 is a section taken on the line 11—11 of Fig. 10, but with the movable parts turned at an angle of 90°; Fig. 12 is a transverse section across the label guide; Fig. 13 is a plan of the stacking chute, showing its relation to the third carrier; Fig. 14 is a section taken on the line 14—14 of Fig. 13; Fig. 15 is a section taken on the line 15—15 of Fig. 14; Figs. 16, 17, 18, 19 and 20 illustrate the various stages of enclosing the article in the inner wrapper and then in the label; Fig. 21 is a perspective view of the wrapped article; and Fig. 22 is a perspective view of the wrapped and labeled article.

The improved wrapping machine comprises in general means for feeding the articles to be wrapped one at a time to the machine; means for placing an inner wrapper in the path of travel of the article into the machine; a series of pockets adapted to hold the articles being wrapped mounted on intermittently movable carriers; a series of plungers for inserting the articles into and ejecting the articles from the pockets; end folding devices cooperating with the plungers and the pockets for folding the ends of the wrapper about the article; means for supplying a label to the machine and for folding it about the wrapped article; and means for discharging the wrapped and labeled article from the machine. The means for feeding the articles and wrappers to the machine, the means for supplying the labels, and the means for stacking the wrapped articles may be of any usual or preferred construction; the other parts of the machine are believed to be broadly novel either in their construction or mode of operation.

More particularly considered, the improved wrapping machine, as illustrated in the drawings, comprises a transport system for transporting the articles to be wrapped through the machine for the various wrapping operations. This transport system includes a series of intermittently movable carriers on which are mounted the spaced pockets for holding the articles to be wrapped and a series of plungers for inserting the articles in the pockets and ejecting them therefrom. In the preferred form of

the invention the intermittently movable carriers are arranged one above another and are generally indicated in Fig. 6 by the reference numerals 5, 6 and 7. On carrier 5 is mounted a series of equally spaced pockets 70 8, and on carrier 6 is mounted a series of equally spaced pockets 9 corresponding to pockets 8. On carrier 7 is mounted a series of pockets 10. The carriers travel in the directions indicated by the arrows in Fig. 6. 75 The article to be wrapped is first inserted with its wrapper in one of the pockets of carrier 6. The partially wrapped article is then transferred to one of the pockets of carrier 5. While the article is in this pocket, 80 the folding operations on the wrapper are completed. The wrapped article is then returned to one of the pockets of carrier 6 (in the preferred form of the invention, to the same pocket). Previous to the transfer of 85 the article from carrier 5 to carrier 6, a label is positioned between the two aligned pockets so that the insertion of the wrapped article and label into the pocket on carrier 6 partially folds the label. The partially 90 labeled article is then transferred to one of the pockets of carrier 7 by which the folding of the label is completed and then the wrapped and labeled article is discharged from the machine. 95

The articles to be wrapped may be supplied to the machine by a conveyer or they may be stacked in a hopper, as shown at 11 in Figs. 1 and 2. Whether a conveyer or a hopper is to be used will depend upon the 100 character of the articles to be wrapped. These devices are of well-known construction and need no detailed description. Briefly, the hopper consists of an adjustable frame construction supported from the rods 105 12 which extend transversely of the machine and are secured in the frame 13 thereof, which is supported on the legs 14. The hopper is open at top and bottom. A reciprocating plunger 15 mounted on the guides 110 16 passes under the hopper and carries the lowermost article into the pocket of the carrier 6 then in alignment therewith. The plunger 15 is actuated from a crank 17 (Fig. 5) mounted on the front end of the main 115 cam shaft 18 journaled in the left hand end of the machine. The crank 17 is connected by a rod 19 with one arm 20 of a bell-crank secured to the shaft 21, the other arm 22 of the bell-crank being connected by a link 23 120 with the support 24 on which the plunger 15 is mounted.

Previous to the reciprocation of the plunger 15 which inserts the unwrapped article in the aligned pocket of carrier 6, an inner wrapper is positioned in the path of travel of the article. The roll of paper or tin foil 25, from which the inner wrappers are cut, is mounted on a rod 26 supported from brackets 27 secured to the top of the 125 130

machine. The strip of wrapper material 28 is passed from the supply 25 under a roll 29 and over the roll 30 yieldingly supported from the upright brackets 31. From the 5 roll 30 the strip of wrapper material passes down through the chute 32 and between the feed rolls 33, and the knife blades 34 to the support 35. These parts are of well-known construction and operation. The feed rolls 10 are driven from a sprocket 37 mounted on the shaft 38. Sprocket 37 is connected with the sprocket 39 mounted on the feed shaft 40 by means of the chain 41. The movable blade of the paper cutter is loosely mounted 15 on the upright rod 43 of the wrapper guiding construction. The movable cutter blade is actuated from the cam 45 (Fig. 3) mounted on the main cam shaft 18. A cam roll 46 mounted on the arm 47 travels in a cam path 20 formed in the side of the cam 45. The arm 47 is secured to one end of a shaft 44 journaled in the machine frame. On the opposite end of the shaft 44 is a downwardly depending arm 48 connected by means of a 25 rod 49 with an arm 50 (Fig. 2) pivoted on a bracket 51. The movable cutter blade is provided with an arm 52 having a suitable connection with the arm 50. These parts being of usual construction and mode of operation 30 need no further description. The movable cutter blade is actuated to sever the wrapper when the latter has been properly positioned in front of the plunger 15.

The carrier 6 which first receives the unwrapped article and its wrapper comprises 35 two sprocket wheels 54 and 55 connected by the chains 56. The sprockets 54 are mounted on the shaft 38 which extends transversely across the machine and is journaled in the side walls thereof. The sprockets 55 are mounted on a stud 58 secured in a bracket 59 (Fig. 2). The rear end of shaft 38 extends beyond the machine frame and supports a number of gears by 40 which shaft 38 and other parts of the machine are driven. Shaft 38 is actuated intermittently from a Geneva gear construction. The Geneva gear is driven from the main shaft 60 to which power may be supplied in any preferred manner. The main shaft 60 extends across the top of the machine and on its front end carries a hand wheel 61; on its rear end it carries a clutch 62 operated by a shifting device 63.

45 The main shaft 60 carries a pinion 65 (Fig. 3) which meshes and drives a gear 66 mounted on the cam shaft 18. On the rear end of the cam shaft is mounted a pinion 67 which meshes with and drives a gear 68 mounted on a shaft 69 (Fig. 7) which also supports the constantly rotating element 70 of the Geneva gear. The constantly rotating part 70 of the Geneva gear carries two rolls 71 which are adapted to enter the slots 65 72 of the intermittently rotating part 73

mounted on the stud 74. Secured to the intermittently rotating part 73 is a gear 75 which meshes with the gear 76 secured to the shaft 38. Thus intermittent movements are imparted to the shaft 38 and to the 70 carrier 6.

On the carrier 6 is mounted the series of 75 equally spaced pockets 9; each pocket consists of two walls (Fig. 1), a fixed wall 78 and a yieldingly mounted wall 79. The pocket walls are supported from brackets which rise from a base 80 secured to the sprocket chain 56. In order that the pockets of carrier 6 may be brought into proper alinement with the pockets of the other carriers, the sprocket wheels 54 and 55 are provided with the four-armed pocket guides 81 which are arranged on the shaft 38 and stud 58 with the sprocket wheels. On the outer end of each arm of the pocket guides 81 is a notch 82 adapted to receive a series of equally spaced lugs 83 secured to the inner side of the sprocket chains 56. This construction permits the pockets of carrier 6 to be brought into proper alinement with the pockets of the other carriers. The alinement of the pockets is further provided for by the adjustable connection 84 between the shaft 38 and the free end of the stud 58.

Carrier 5 and its pockets 8 are constructed substantially like carrier 6 and its pockets 9. The pockets on the two carriers are correspondingly arranged. Carrier 5 comprises the sprocket wheels 86 and 87 connected by the sprocket chains 88 which support the pockets 8. Sprocket wheels 86 are mounted on a shaft 89 which extends across the machine and is journaled in the side walls thereof. Sprocket wheels 87 are mounted on the stud 90 which is supported from the frame of the machine in the same manner that stud 58 is supported. An adjustment rod 91 connects shaft 89 with the free end of stud 90. The rear end of shaft 89 projects beyond the frame of the machine and is provided with a gear 92 which meshes with and is driven by a gear 93 mounted on shaft 38. Thus the shaft 89 and carrier 5 are actuated intermittently 105 and in timed relation with the intermittent movements of shaft 38 and carrier 6.

Following the insertion of the unwrapped article and its wrapper in one of the pockets 9 of carrier 6 by plunger 15, carrier 6 is actuated to bring the pocket containing the partially wrapped article opposite the corresponding pocket in carrier 5, as indicated in Fig. 6. Thereupon the carriers momentarily come to rest and the oppositely disposed fingers 95 (Fig. 9) are actuated to transfer the partially wrapped article from the pocket 9 of the carrier 6 to the alined pocket 8 of carrier 5, thereby completing the side folds of the wrapper. 115 120 125 130

Plungers 95 are arranged to reciprocate vertically, passing through pocket 9 to eject the article therefrom, and insert it in pocket 8 and returning to normal position below 5 pocket 9. For this purpose plungers 95 are mounted on the lower ends of vertically disposed slides 96 mounted in top guides 97 and bottom guides 98, suitably supported from the frame of the machine. The upper 10 ends of slides 96 are pivotally connected by links 99 with rocker arms 100 secured to the rock shaft 102. Intermittent rocking movements are imparted to the shaft 102 from a cam 103 mounted on the front end 15 of the main cam shaft 18 by means of a lever 104 loosely mounted on the main driving shaft 60 and a link 105 adjustably secured to an arm 106 depending from the shaft 102. The lever arm 104 carries a roll 20 which travels in the cam groove 107 cut in the side of the cam 103. It will thus be seen that as the cam 103 rotates the slide 96 is intermittently vertically reciprocated.

The partially wrapped article is positioned in the pocket of carrier 5 with the end extensions of the wrapper projecting beyond the ends of the pocket, as indicated at 109 in Fig. 8. The ends of the article are indicated by the dotted lines 110. It 25 will be observed that the wall 111 of the pocket is substantially as long as the article to be wrapped, but that the wall 112 is considerably shorter than the article. The reason for this discrepancy in the length of the 30 walls will presently appear. When the partially wrapped article has been inserted in the pocket in carrier 5 and the plungers 95 have returned to normal position, the carriers are again actuated. This movement of 35 the partially wrapped article carries it between the stationary end folders 114 by which the end extensions of the wrapper are folded at right angles to the length of the article. In the illustrated embodiment of 40 the invention, the end folders 114 are brushes, which are particularly adapted for use when the article is relatively wide and thin and the inner wrapper is tin foil. According to the size and construction of the 45 article to be wrapped and the material of which the inner wrapper is composed, different types of stationary end folders are employed. The brushes 114 are adjustably mounted in the ends of holders 115 secured 50 to heads 116 supported by the rods 117 from the brackets 118 (Fig. 9) secured to the frame of the machine.

Inasmuch as the ends of wall 112 of the 55 pocket are removed, it will be obvious that a proper end fold cannot be made by the stationary end folders as the article is carried past the end folders unless means are provided for taking the place of the removed ends of the pocket. In order that a transverse crease may be made at the ends of the

article during the passage of the article past the end folders 114, fold breakers 120 are arranged to follow after the article and come in contact with the end extensions of the wrapper as they pass between the end folders 114, as illustrated in dot and dash lines in Fig. 8. These fold breakers 120 (Fig. 1) are vertically arranged plates secured to the lower ends of downwardly extending arms 121 secured to a rock shaft 122 pivoted in brackets 123 rising from the top of the machine. Rocking movements are imparted to the shaft 122 from the cam 125 mounted on the cam shaft 18 by a rod 126 (Figs. 1 and 9), pivotally connected at one end with an arm 127 depending from the rock shaft 122. The bifurcated other end of the rod 126 straddles the shaft 18 and carries a cam roll 124 held in engagement with the periphery of the cam 125 by means of the coil spring 128 (Fig. 9) one end of which is secured to the shaft 122 and the other end of which is secured to the bracket 123. The fold breakers 120 are normally in the position shown in Fig. 1. The movements of the fold breakers are so timed that when the carrier 5 begins to move to carry the article past the end folders 114, the fold breakers overtake the article so that the partial end fold is made against the fold breakers, as shown in dot and dash lines in Fig. 8. When the partial end folds have been made and the fold breakers 120 have been retracted to normal position, the pocket holding the partially wrapped article momentarily comes to rest, as indicated at 129 in Fig. 8. During the next intermittent movement of the carrier, the article is forced between the inturned ends 130 of the yieldingly mounted movable end folders 131. The movable end folders 131 are pivotally supported at 132 on the heads 116 and are normally pressed inwardly to the position shown in Fig. 8 by springs 133. When the article has passed beyond the movable end folders 131, the ends 130 thereof return to normal position and thereby fold the end extensions of the wrapper down flat against the wrapped surface of the article, as indicated at 134. This series of movements completes the folding of the wrapper about the article. The wrapped article is now in condition for receiving the label.

The wrapped article is discharged from the carrier 5 by plungers 137 secured to vertically reciprocating slides 138 mounted to slide in guides 139 secured to the frame of the machine. The upper ends of slides 138 are pivotally connected by links 140 with the arms 136 secured to shaft 102. In the preferred form of the invention there are as many pockets mounted on carrier 5 as there are pockets on carrier 6, therefore when the wrapped article is returned to carrier 6 it is reinserted in the same pocket in which it

was originally positioned. If, however, there are fewer pockets mounted on carrier 5 than on carrier 6, the wrapped article will be received by a different pocket on carrier 6.

5 Previous to the transfer of the wrapped article from carrier 5 to carrier 6, a label is positioned between the alined pockets. Any preferred construction of paper feeding mechanism may be employed for delivering the labels one at a time to the machine. The labels are taken from the point of delivery to the machine and transferred to the point between the alined pockets where it will be engaged by the wrapped article and 10 carried with it into the opposite pocket to thereby partially fold the label about the article. The label transferring means comprises a platform 145 supported on a bracket 144 (Figs. 10 and 11) secured to the lower 15 end of a vertically arranged shaft 146 journaled in a hub 147 integral with a bracket 148 extending transversely of the left hand end of the machine. The platform 145 is arc-shaped and is of such length that while 20 one end is positioning a label between the alined pockets the other end may act as a guide for the incoming label delivered to the machine. In the illustrated embodiment of the invention, the labels are delivered to the machine at right angles to the position the labels occupy when they are in 25 place to be folded about the wrapped article.

Fig. 2 shows the position of the platform as it receives the label 150 from the delivering means, and Fig. 10 shows the position of the platform as it holds the label in place to be engaged by the wrapped article as the latter is transferred to the pocket of carrier 6. This movement through an angle 30 of 90° is imparted to the shaft 146 which supports the platform by means of a cam 151 mounted on the cam shaft 18. The connections between the cam 151 and the shaft 146 comprise an arm 152 secured to the shaft 35 44 and carrying on its free end a roll which travels in a cam path formed in the side of the cam 151. On the forward end of the shaft 44 is mounted a bevel gear 155 which meshes with and drives a bevel pinion 156 secured to the upper end of the shaft 146. Thus the platform is moved intermittently in 40 timed relation with the movements of the carriers 5 and 6.

When the platform has released a label 45 between the alined pockets and it has swung to position to receive the next incoming label, the turned-up edge 158 of an end extension 159 adjustably secured to the platform engages the label which has just been delivered to the machine and presses it against the lateral side of an adjustable guide 160 secured to and extending rearwardly from the front frame of the machine. By this means the label is properly positioned on the platform. Thereupon the

clamp arm 162 provided at its free end with a felt gripping means 163 is actuated to press and hold the label firmly against the platform. The clamp arm 162 is pivotally mounted at 164 on an ear 165 rising from the bracket 144. The clamp arm 162 is actuated to hold the label against the platform and to release the label by means of a cam 166 mounted on the cam shaft 18. The connections between the cam 166 and the clamp 70 162 comprise a cam roll 167 carried by the upper end of a rod 168. The rod 168 is bifurcated and straddles the cam shaft 18. The lower end of the rod 168 (which is adjustable in length) is pivotally connected 75 with a horizontally disposed link 169 pivotally connected at its other end with a boss 170 depending from the bracket 148. The link 169 is provided with a lug carrying a pin 172 which is engaged in a groove formed in a collar 173 loosely mounted on the shaft 146. Also engaged in the grooved collar 173 is a pin 174 projecting laterally from the clamp arm 162. Thus the active part of the cam 166 serves to raise the clamp arm 80 90 162 and release the label. This occurs when platform 145 and the label 150 are in the position shown in Fig. 10. The clamp is depressed to hold the label against the platform by the force of gravity. Thus the 95 roll 167 is held in contact with the cam 166 by the weight of the parts connected with it.

The feeding mechanism for delivering the labels one at a time to the machine comprises a platform 175 upon which the labels are stacked, as shown in Fig. 3. The platform 175 is mounted on the upper end of a vertically arranged rack 176 engaged and operated by a spring-driven pinion 177. This construction, which is supported from the front of the machine by a bracket 178, is well-known and requires no further description. The labels are pressed upwardly against the holding needle 180 supported on an arm 181 adjustably secured in a bracket 182. The labels are stripped from the pile and delivered in the machine one at a time by a rubber, ratchet-controlled wheel 183 (Fig. 11) when the pawl 184 is in engagement with the ratchet wheel 185. When the pawl 184 is out of engagement with the ratchet wheel, the rubber wheel 183 travels back and forth on the pile of labels without delivering them. The wheel 183 is carried by the offset end of a lever 186 pivotally mounted on the lower end of an arm 188 secured to the shaft 189 journaled in brackets extending from the top of the machine. The wheel 183 is yieldingly held in engagement with the pile of labels by a spring 190. The arm 188 is oscillated to cause wheel 183 to travel back and forth on the pile of labels by means of a crank 192 (Fig. 2) mounted on a shaft 193 journaled in the front of the machine. The crank 192 is connected by a 100 105 110 115 120 125 130

link 194 with the lower end of an arm 195, the upper end of which is secured to the shaft 189.

The rearward movement of the wheel 183 serves to insert the topmost label between the upper and lower rolls which deliver the label to the machine. The upper set of rolls 197 (Fig. 4) are mounted on the shaft 193 and travel in a clockwise direction, viewing Fig. 3. The lower set of rolls 198 are secured to a shaft 199 journaled in the forward ends of arms 200 pivotally mounted on a bracket 201. The rolls 198 are held in yielding engagement with the rolls 197 by means of the spring 202. The rolls 198 are driven in a counter-clockwise direction (viewing Fig. 3) and for this purpose the shaft 193 is provided with a gear 203 which meshes with a gear 204 mounted on the shaft 199. The left hand end of the shaft 193 carries a bevel gear 206 which meshes with a corresponding gear 207 fixed on a shaft 208 journaled in the machine frame. The other end of the shaft 208 carries a sprocket wheel 209 which is driven by a second sprocket wheel 210 mounted on the cam shaft 18. The sprocket wheels are connected by a chain 211. Proper tension is imparted to the chain by an idler sprocket 212 mounted on the stud 213. Thus the feed rolls 197 and 198 are driven intermittently in timed relation with the other moving parts of the machine.

The feed rolls 197 and 198 deliver the label in position to be clamped against the platform 145. Labels for different sizes of articles vary in length. Some labels are of such length that it is not expedient that they pass entirely through the feed rolls before they are gripped and swung into position between the alined pockets. When this is the case, and in order that the labels may move freely from between the feed rolls, the shaft 193 is provided with a cam 215 (Fig. 4), the active part of which is adapted to contact with a roll 217 mounted on the shaft 199 and thereby swing the shaft 199 downwardly and the rolls 198 out of contact with the label and the rolls 197. When the active part of the cam 215 has passed out of engagement with the roll 217, the spring 202 returns the shaft 199 to normal position in engagement with the rolls 197. As the label is swung from the point of delivery to the point where it is positioned between the alined pockets, the free, unsupported end of the label passes between upper and lower guide rods 218 and 219 (Fig. 11). The feed rolls 197 and 198 deliver the labels to the machine between an upper guide 220 having an up-turned forward end 221 and a lower guide 222. The swing of the platform into position to receive the label and into position to deliver the label between the alined pockets is de-

termined respectively by the stop rods 224 and 225 (Fig. 2).

As the wrapped article is transferred by the plungers 137 into the alined pocket 9 of carrier 6, the wrapped article engages 70 the label 150 (see Fig. 18) and carries it with it into the receiving pocket. This movement partially folds the label about the article, as indicated in dot and dash lines. Carrier 6 is then actuated to bring the 75 partially labeled article to the position indicated in Fig. 19 with the unfolded end of the label extending outwardly and resting on a support 226. While the label is in this position, a paste applying roll 227 80 mounted in the lower open end of a paste pot 228 is brought into engagement with the end of the label. The paste pot 228 is adjustably supported on the bell-crank arm 229 (Fig. 1) secured to the shaft 230. The 85 other arm 231 of the bell-crank is pivotally connected with the lower end of a rod 232, the upper bifurcated end 233 (Fig. 3) of which straddles the cam shaft 18 and carries a roll in engagement with the cam 234 90 mounted on the cam shaft. The paste applying device is thus actuated in timed relation with the other parts of the machine to apply paste to the label when the latter occupies the position shown in Fig. 19. 95

As the paste pot is swung into paste applying position the ratchet wheel 236 travels over the pivotally and yieldingly mounted rack 237. The construction is such that the movement of the paste pot into 100 paste applying position depresses the rack 237, and the engagement of the ratchet wheel with the rack teeth causes the paste roll 237 to be turned to expose a fresh surface of paste to the label. The pawl 238 105 prevents the rotation of the paste roll in the opposite direction. The spring 239 (Fig. 3) returns the rack 237 to normal position. The construction and mode of operation of the paste applying device are 110 old and well-known.

After the paste has been applied to the label, the carrier 6 is again advanced and then comes to rest in the position shown in Fig. 20. As the partially labeled article 115 is swung into this position, the outstanding end of the label encounters a yieldingly mounted drag 240 which serves to draw the label tightly about the article. When the carrier has come to rest, plungers 241 secured to the lower ends of the slides 188 are actuated to transfer the partially labeled article into the opposite alined pocket 10 of carrier 7, thereby completing the labeling of the article. 120

In order that the glue may set sufficiently to permit the wrapped and labeled article to be ejected from carrier 7, the carrier rotates in the direction indicated by the arrow in Fig. 6 to the point of delivery which 125

is indicated at 243. Carrier 7 is driven intermittently in timed relation with the movements of carriers 5 and 6, and for this purpose carrier 7 is mounted on a shaft 245 which extends transversely of the machine and carries on its rear end a gear 246 which meshes with and is driven by a gear 247 mounted on the shaft 38. Carrier 7 is provided with only four pockets which are mounted on a hub 248. The manner of mounting the pockets 10 on carrier 7 is substantially the same as the manner of mounting the pockets on carriers 5 and 6, that is to say, one wall of the pocket is fixed and the other is yielding.

When the wrapped and labeled articles are brought to the point of discharge 243 (Fig. 6) they are discharged from the carrier by a pair of horizontally reciprocating plungers 250 mounted on slides 251 reciprocating in guides 252. The plungers 250 are reciprocated from the front rocker arm 100 through a vertically arranged rod 254 (Fig. 5), the upper end of which is pivotally connected with the rocker arm and the lower end of which is pivotally connected with an arm 255, secured to a shaft 256 which extends transversely of the machine, and is journaled in the front and rear walls thereof. Arms 257 secured to and depending from the shaft 256 are connected by links 258 with the rear ends of the slides 251. Thus the horizontally reciprocating plungers 250 are actuated in timed relation with the vertically reciprocating plungers.

The wrapped and labeled articles discharged from carrier 7 are received by a platform 260 (Figs. 13 and 14) mounted on a lever arm 261 secured to a shaft 262 extending transversely across the machine. On the rear end of the shaft 262 is mounted a crank 263. The shaft 262 is oscillated in timed relation with the movements of the other parts of the machine from a cam 265 (Fig. 7) mounted on the cam shaft 18. A cam roll 266 mounted on an arm 267 pivoted at 268 travels in a path formed in the side of cam 265. The free end of arm 267 is connected with crank 263 by a rod 269. The receiving platform 260 is arranged to deliver the wrapped and labeled articles in the bottom of the stacking chute 271.

The stacking chute 271 is composed of two sides 272 and a bottom 273 which are obliquely arranged, as shown in Fig. 14. The bottom 273 is supported from the bracket 274 and the sides 272 are adjustably supported from the rods 277. In the lower ends of the side walls 272 of the stacking chute are pivotally and yieldingly mounted gates or article supports 275. Springs 276 act to press the upper ends 278 of the supports inwardly to keep the

stacked articles in the chute, as indicated in Fig. 15. When the receiving platform, 260 is actuated to insert a freshly wrapped and labeled article in the bottom of the chute, the supports 275 are forced outwardly. When the platform 260 with its article has passed beyond the upper ends 278 of the supports 275, the springs 276 act to return the supports to normal position to prevent the egress of the newly inserted article. The length of the platform is such that it passes freely between the supports while they are in normal position.

The operation of the improved wrapping machine has been indicated in connection with the description of the construction of the various parts of the machine. The passage of an article through the machine and the various wrapper folding operations will be briefly recapitulated. The unwrapped article is indicated at 280 (Fig. 6) and the wrapper in which it is to be enclosed is indicated at 281. The forward movement of plunger 15 inserts the article and wrapper in the aligned pocket 282 of carrier 6, thereby partially folding the wrapper about the article, as shown in Fig. 16. Carrier 6 is then actuated and the article 280 comes to rest at 283 (Figs. 6 and 17). As the article passes from point 282 to point 283, the outstanding side of the wrapper passes under a yieldingly mounted guide 285 by which the side extension 284 (Fig. 17) of the wrapper is bent downwardly. When the carrier has come to rest, the plungers 95 are actuated to insert the article in the oppositely disposed pockets 286 of carrier 5, thereby completing the side folds of the wrapper. During the next two intermittent movements of carrier 5, the article is passed between the stationary and movable end folders, as indicated in Figs. 8 and 18, whereby the end extensions of the wrapper are folded down against the wrapped side of the article. At the finish of the end folding operations, the wrapped article occupies the position indicated at 287. The label 150 having been positioned under the wrapped article, the plungers 137 are actuated to reinsert the article and at the same time the label in pocket 288 of carrier 6, which is the same pocket in which the plunger 15 first inserted the article. The next intermittent movement of carrier 6 brings the wrapped and partially labeled article to position 289 (Fig. 6), which is the position shown in Fig. 19. During the momentary dwell of the carrier, paste is applied to the outstanding end of the label. Thereupon the article is brought to position 290, this being the position shown in Fig. 20. While the carrier is at rest, the plungers 240 are actuated to insert the article in the oppositely disposed pocket 291, thereby completing the

5 folding of the label about the wrapped article, as indicated in dot and dash lines in Fig. 20. While the wrapped and labeled article is traveling from the point 291 to the
10 point 292, the glue has had time to set so that the article may be discharged from carrier 7. This is done by plungers 250. The discharged article is then placed in the stacking chute 271 by the swinging platform 260.

15 It will be understood that the wrapping machine of the present invention, as illustrated in the drawings and as described above, is susceptible of many changes and modifications within the scope of the invention which is defined by the following claims. The novel form of label feeding or transferring mechanism described herein and illustrated in the drawings is the subject-matter of a divisional application filed
20 by us November 10, 1923, Serial No. 674,063.

What we claim as new is:—

25 1. A wrapping machine having in combination, a series of intermittently movable carriers, spaced pockets mounted on the carriers, means for inserting an article and a wrapper in a pocket of one of the carriers, means for transferring the partially wrapped article to a pocket of another carrier, and means for returning the wrapped article and a label to the same pocket of the first carrier.

35 2. A wrapping machine having in combination, a series of intermittently movable carriers, spaced pockets mounted on the carriers, and a series of plungers for inserting articles in the pockets of the first carrier, for transferring the articles to the second carrier, for returning the articles to the first carrier, for transferring the articles from the first to the third carrier and for discharging the articles from the machine.

45 3. A wrapping machine having in combination, a series of three intermittently movable carriers, spaced pockets mounted on the carriers, means for inserting articles in the pockets of the middle carrier, means for transferring the articles to the pockets of the second carrier, means for returning the articles to the pockets of the middle carrier, means for transferring the articles to the third carrier, and means for discharging the articles from the machine.

55 4. A wrapping machine having in combination, a series of carriers, pockets mounted on the carriers, means for inserting an article and a wrapper in a pocket of one carrier, means for transferring the article and wrapper to a pocket of a second carrier to complete folding the sides of the wrapper, the end extensions of the wrapper projecting beyond the ends of the pocket on the second carrier, means for folding the

end extensions of the wrapper against the article, means for transferring the wrapped article and a label to a pocket on the first carrier, means for transferring the article to a pocket of a third carrier to complete the folding of the label, and means for discharging the wrapped and labeled article from the machine.

5 5. A wrapping machine having in combination, a series of carriers, pockets mounted on the carriers, means for inserting a series of articles and wrappers in the pockets of one carrier, means for transferring the articles and wrappers to the pockets of a second carrier, the end extensions of the wrappers projecting beyond the ends of the pockets on the second carrier, stationary folders located in the path of travel of the end extensions of the wrappers, fold breakers against which the end folds of the wrappers are made as the articles move past the stationary folders, and means for moving the fold breakers into and out of operative position.

6 6. A wrapping machine having in combination, a series of carriers, pockets mounted on the carriers, means for inserting an article and a wrapper in a pocket of one carrier, means for transferring the article and partially folded wrapper to a pocket of a second carrier to complete the side folds of the wrapper, the end extensions of the wrapper projecting beyond the ends of the pocket of the second carrier, stationary end folders located in the path of travel of the article, means for moving the article past the end folders to fold the end extensions of the wrapper at right angles to the length of the article, and movable means against which the partial end folds are made.

7 7. A wrapping machine having in combination, a series of intermittently movable carriers, pockets mounted on the carriers, a plunger for inserting an article and a wrapper in a pocket of one carrier, means for transferring the article and wrapper into a pocket of a second carrier, one wall of the pocket of the second carrier being substantially shorter than the other wall and the article positioned in the pocket, and means for folding the end extensions of the wrapper down directly against one side of the wrapped article.

8 8. A wrapping machine having in combination, a series of intermittently movable carriers, pockets mounted on the carriers, a plunger for inserting an article and a wrapper in a pocket of one carrier, a plunger for transferring the article and wrapper to a pocket of a second carrier, one wall of the pocket of the second carrier being substantially shorter than the article positioned in said pocket, stationary end folders for folding the end extensions of the wrapper at right angles to the length of the article,

movable fold breakers against which the partial end folds are made, and yieldingly mounted end folders for folding the end folds down against one side of the wrapped article.

9. A wrapping machine having in combination, a series of intermittently movable carriers, spaced pockets mounted on the carriers, a plunger for inserting an article and 10 a wrapper in a pocket of one carrier, a second plunger for transferring the article and wrapper to a pocket of a second carrier, and end folders for folding the end extensions of the wrapper projecting beyond the ends 15 of the pocket in which the article is positioned comprising stationary folders and yielding folders for turning the end extensions to a position at right angles to the article normally in operative position, said 20 yielding folders being pushed outwardly by the travel of the article past them, and returning inwardly to complete the end folds when the article has passed beyond them.

10. A wrapping machine having in combination, a carrier, pockets mounted on the carrier, each pocket consisting of spaced walls adapted to hold an article to be wrapped, the walls of the pocket being of such length that the ends of the wrapper extend beyond the ends of the walls, movable 30 folders for folding the ends of the wrapper down directly against one side of the wrapped article, and means for inserting the article in the pocket and for ejecting it 35 therefrom.

11. A wrapping machine having in combination, a carrier, pockets mounted thereon, means for inserting partially wrapped articles in the pockets so that the end extensions of the wrappers project beyond the ends of the pockets, one wall of each pocket being substantially shorter than the other wall and the article positioned therein, and means for folding the end extensions of the 45 wrappers down directly against the wrapped articles.

12. A wrapping machine having in combination, an intermittently movable carrier, pockets mounted on the carrier, means for 50 inserting partially wrapped articles in the pockets so that the end extensions of the wrappers project beyond the ends of the pockets, stationary and movable end folders between which the articles pass, fold breakers adapted to be brought in contact with the partially wrapped articles at the beginning of the end folding operation and against which the partial end folds are made, and means for actuating the fold breakers.

- 60 13. A wrapping machine having in combination, an intermittently movable carrier, pockets mounted on the carrier, means for inserting partially wrapped articles in the pockets with the end extensions of the wrap- 65 pers projecting beyond the ends of the

pockets, end folders between which the partially wrapped articles are passed, fold breakers arranged to be brought in contact with the wrapped articles at the point where the end folds are made, and means for actuating the fold breakers. 70

14. A wrapping machine having in combination, a series of intermittently movable carriers, pockets mounted on the carriers, means for inserting an article and a wrapper 75 in a pocket of one carrier, means for transferring the partially wrapped article to a pocket of a second carrier, means for completing the wrapping of the article, and means for reinserting the wrapped article 80 and a label in the same pocket of the first carrier in which the article was originally positioned.

15. A wrapping machine having in combination, a series of intermittently movable carriers, means for inserting an article and a wrapper in a pocket of one carrier, means for transferring the partially wrapped article to a pocket of a second carrier, means for completing the wrapping of the article, 85 means for reinserting the wrapped article and a label in the same pocket of the first carrier, and means for transferring the wrapped and partially labeled article to a pocket of a third carrier to complete the 90 folding of the label.

16. A wrapping machine having in combination, a series of intermittently movable carriers arranged one above another, spaced pockets mounted on the carriers, means for 100 inserting an article and a wrapper in a pocket of the middle carrier, means for transferring the partially wrapped article to a pocket of the uppermost carrier, means for completing the folding of the wrapper, 105 means for holding a label in a horizontal position under the wrapped article, means for inserting the wrapped article and the label in a pocket of the middle carrier, and means for transferring the wrapped and 110 partially labeled article to a pocket of the lowermost carrier to complete the folding of the label.

17. A wrapping machine having in combination, a plurality of intermittently movable carriers arranged one above another, pockets mounted on the carriers, the pockets of the upper carrier being adapted to hold wrapped articles, means for holding a label horizontally beneath the wrapped article, 115 and means for transferring the wrapped article and the label directly to a pocket of the lower carrier.

18. A wrapping machine having in combination, a series of intermittently movable carriers arranged one above another, spaced pockets mounted on the carriers, a horizontally movable plunger for inserting an article and wrapper in a pocket of the middle carrier, a vertically movable plunger 125 130

for transferring the partially wrapped article into a pocket of the uppermost carrier, means for folding the ends of the wrapper, a second vertically movable plunger for 5 transferring the wrapped article and a label to a pocket of the middle carrier, a third vertically movable plunger for transferring the wrapped and partially labeled article into a pocket of the lowermost carrier to 10 complete the folding of the label, and a second horizontally movable plunger to discharge the wrapped and labeled article from the machine.

19. A wrapping machine having in combination, a series of intermittently movable carriers, spaced pockets mounted on the carriers, the carriers being arranged so that a pocket on the upper carrier is vertically disposed above a pocket on the lower carrier 20 when the carriers come to rest, means for inserting an article and a wrapper in a pocket of the upper carrier, means for holding a label in a horizontal position between the two aligned pockets, vertically movable arms 25 for transferring the wrapped article from the upper carrier to the lower carrier, where-

by the label is carried with the wrapped article into the pocket on the lower carrier, and a plunger for discharging the wrapped and labeled article from the lower carrier. 30

20. A wrapping machine having in combination, a series of carriers having means for holding the articles during the wrapping operations, means for feeding the articles to one carrier, means for transferring 35 the articles to another carrier, means for returning the articles to the first carrier, and means for transferring the articles to the last carrier, during which movements the articles are enclosed in a wrapper and a 40 label.

21. A wrapping machine having in combination, a plurality of carriers having means for holding the articles during the wrapping operations, means for feeding the 45 articles to one carrier, means for transferring the articles to another carrier, and means for returning the articles to the first carrier, during which movements the articles are enclosed in a wrapper.
